US0D1035678S

(12) **United States Design Patent** (10) Patent No.: **US D1,035,678 S**
 Lim et al. (45) Date of Patent: ** Jul. 16, 2024

(54) **DISPLAY SCREEN OR PORTION THEREOF WITH GRAPHICAL USER INTERFACE**

(71) Applicant: **SAMSUNG ELECTRONICS CO., LTD.**, Suwon-si (KR)

(72) Inventors: **Eunsil Lim**, Suwon-si (KR); **Yeonjoo Jwa**, Suwon-si (KR)

(73) Assignee: **SAMSUNG ELECTRONICS CO., LTD.**, Gyeonggi-Do (KR)

(**) Term: **15 Years**

(21) Appl. No.: **29/822,506**

(22) Filed: **Jan. 10, 2022**

(30) **Foreign Application Priority Data**

Jul. 23, 2021 (KR) 30-2021-0035129

(57) **CLAIM**

The ornamental design for a display screen or portion thereof with graphical user interface, as shown and described.

DESCRIPTION

FIG. 1 is a front view of a first embodiment of a display screen or portion thereof with graphical user interface, showing our new design; and,

FIG. 2 is a front view of a second embodiment of a display screen or portion thereof with graphical user interface, showing our new design.

The outermost perimeter illustrated by dashed broken lines represents a display screen or portion thereof and forms no part of the claimed design. The remaining dashed broken lines illustrating portions of the graphical user interface form no part of the claimed design.
